UNITED STATES PATENT OFFICE.

ARTHUR DREW, OF BUFFALO, WYOMING.

COMBINED HALTER AND BRIDLE.

1,216,966.

Specification of Letters Patent. Patented Feb. 20, 1917.

Application filed April 3, 1916. Serial No. 88,550.

To all whom it may concern:

Be it known that I, ARTHUR DREW, a citizen of the United States, residing at Buffalo, in the county of Johnson and State of Wyoming, have invented new and useful Improvements in Combined Halters and Bridles, of which the following is a specification.

This invention relates to combined halters and bridles, and it has for its object to produce a simple and effective halter which may also be utilized as a hackamore riding bridle or driving bridle.

A further object of the invention is to produce an improved halter which may be effectively and inexpensively constructed of rope in connection with metallic clamp plates, the improved halter being one of exceptional strength and durability.

20 A further object of the invention is to produce a halter which may be made of two pieces of rope in connection with metallic clamp plates and in such a manner as to avoid as far as possible the use of joints whereby the structure will be weakened.

A further object of the invention is to produce a halter which by the addition of a bit may be utilized as a riding bridle and which by the further addition of blinders may be used as a driving bridle.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—

Figure 1 is a perspective view of the improved halter.

Fig. 2 is a perspective view, showing the halter with the addition of bit and blinders.

Figs. 3 and 4 are perspective views showing, separated from each other, the two parts of the improved bridle, each of which is made of a single piece of rope or other material.

Fig. 4^a is an enlarged detail view of the

loop 33 and adjacent parts, the rope parts having been loosened for the sake of clearness.

Fig. 4^b is a perspective detail view of the plate J detached.

Figs. 5, 6 and 7 are detail views of the different clamping plates used in connection with the device.

Fig. 8 is a perspective view showing one of the blinders detached.

Corresponding parts in the several figures are denoted by like characters of reference.

The improved halter is preferably made of rope in connection with connecting and securing devices consisting of clamp plates and the like; two pieces of rope being employed to produce the entire halter. A good quality of rope is preferred on account of lightness, strength and inexpensiveness, but it is desired to be understood that other material, such as leather, may be used.

The two pieces of rope which are designated, respectively, by A and B, are so arranged that one of said pieces, A, will form the crown, one cheek piece and the throat latch, while the other piece, B, will constitute the other cheek piece and the nose band. The rope A, moreover, forms a supporting member for a guide ring through which a loop or bight of the nose strap is guided, said bight carrying a ring with which a tie rope may be connected, said tie link constituting also a stop whereby disengagement of the nose strap from the guide ring is prevented.

Referring now to the drawings, it will be seen that the rope A is doubled to form a loop 15, the side portions of which 16, 17 combine to form the cheek piece C. The side portion 16, or that portion of the rope A which forms an extension thereof is doubled to produce a loop 18, the side portions of which 19, 20 will constitute the crown D. E is a clamp plate or connecting member having vertically disposed substantially parallel sleeves 21 through which the side portions 19, 20 of the loop 18 are guided. Said clamp plate also has a sleeve 22 which is spaced from and disposed substantially at right angles to the sleeves 21. The bight of the loop 18 projects below the sleeves 21, and the side portions thereof are connected together by a clamping ring 23 which will obstruct the withdrawal of the side portions 19, 20 upwardly through the sleeves 21, and which may be adjusted to permit such with-

drawal to be partially effected for the purpose of enabling the bridle to be fitted to the heads of animals of various sizes.

F is a substantially triangular clamp plate 5 having sleeves 24, 25, 26, there being two sleeves 24 which are disposed in axial alignment and which are engaged with the side portions 16, 19 of the loops 15, 18 at the intersection thereof. The sleeve 25 engages 10 the side portion of the loop 15, and the sleeve 26 engages the side portion 20 of the loop 18, thereby firmly connecting these parts of the rope A at the intersection of the cheek piece, the crown and the throat latch. The 15 latter which is designated by G is formed in part by an extension of the side portion 20 of the crown which is doubled on itself to form a loop 27 in the bight of which a snap hook 28 is supported. The side portion 20 of the loop which constitutes the 20 cheek piece has an extension 29. The latter, in conjunction with one side portion 30 of the loop 27, is several times folded to produce a double supporting loop 31 in the bight of which a guide ring 32 is supported, 25 said rope portions being also folded to produce a double loop 33 surrounding the throat latch, the shank portions of the rope intermediate the loops 31, 33 constituting a connecting member or shank 34. The terminals 30 35 of the rope A are secured on the shank by means of a clamp wire 36, and the rope portions constituting said shank or connecting member are connected together near the lower end of the shank by a clamp wire 37.

The rope B is doubled to produce a loop 38, the bight of which is supported in the sleeve 22 of the clamp plate E. The side portions 39, 40 of the loop 38 constitute the 40 second cheek piece H of the halter, and said side portions at their lower ends are engaged with the sleeves 41, 42 of a clamp plate J which is of a construction similar to that of the clamp plate F, said plate being 45 of triangular formation having at the two sides thereof the sleeves 41, 42 and at the third side a pair of axially alining sleeves 43. The side portions 39, 40 are extended and folded to produce coils 44, 45 constituting the nose strap K, a portion of which is 50 guided through the guide ring 32 to produce a loop 46 carrying a tie ring 47, the ring 27 being of such dimensions as to render withdrawal of the loop 46 through the guide 55 ring 32 impossible. The terminals of the rope B are clamped by means of wire clamps 48 on the portions of the coils 44, 45 which go to constitute the loop 46. The coils 44, 45 are confined in sleeves 49 of a clamp plate 60 L which has an additional sleeve 50 engaging the bight of the loop 15, the side portions of which constitute the cheek piece C, which latter is thus connected with one side of the nose band. One of the coils, 45, of the 65 nose strap K is confined in the sleeves 43 of

the clamp plate J which thus serves to connect the other side of the nose band with the cheek piece H.

The clamp plate E is provided intermediate the sleeves 21 and 22 with an eye 51 70 with which the snap hook 28 carried in the bight of the loop constituting the major part of the throat latch G may be connected.

Blinders 52 may be detachably clamped on the cheek pieces of the bridle, said blinders 75 being connected with a bifurcated strap 53 which is detachably connected with the crown D. The clamp plates J and L are each provided with a slot 54, said slot being 80 for the attachment of straps 55 supporting 85 a bit 56. The bit, however, is obviously used only when the device is utilized as a bridle, and the blinders only when the bridle is used for driving purposes. When 90 the device is used as a halter, the bit and 95 the blinders will be detached.

As will be seen from the foregoing description, the component parts of the halter, to wit, the crown, cheek pieces and the nose band are composed each of two leads or 95 thicknesses of rope. Only two pieces or 100 lengths being employed it follows that joints are few in number, thereby insuring great strength which is further insured by the avoidance of stitching, the terminals of each 105 rope being secured by wire clamps. The shank member that connects the throat latch with the nose band is formed of four thicknesses of rope, and the guide ring carried 110 by said shank and through which a looped portion of the nose band is guided permits the nose band to be tightened about the nose 115 of the animal by simply pulling on the tie rope which is connected with the link carried by the looped portion of the nose band, enabling the device to be used as a hackamore 120 in turning or breaking animals. The halter may be very conveniently secured or detached by means of a snap hook 28 engaging 125 the eye 51. An important and valuable feature of the device resides in the facility with 130 which it may be adjusted to fit the heads of animals of various sizes by lengthening or shortening that portion of the loop which constitutes the crown D which extends 135 through the sleeves 21 of the clamp plate E and the side portions of which 19, 20 are clamped together by the ring 23. The several clamp plates may be suitably constructed of malleable iron, it being understood that 140 the sleeves of said clamp plates are bent about the rope members with which they are to be connected, said sleeves being formed, as will be best seen in Figs. 5, 6 145 and 7, by reference to which it appears that 150 the said sleeves are formed with tongues 57 extending through slots 58 in said plates, 155 said tongues being clenched to properly secure the sleeves about the rope portions engaged thereby. The general construction is 160

simple, and a device is produced which is inexpensive and thoroughly useful for the purpose for which it is provided.

Having thus described the invention, 5 what is claimed as new, is:—

1. A halter composed of two pieces of rope, one piece being folded to produce a cheek piece having a loop at its lower end, a crown having a looped extension, a throat 10 latch having a loop, and a looped shank depending from the throat latch; the other piece being folded to produce a cheek piece having a loop at its upper end, and a nose band, the latter including two coils of rope, 15 clamp members whereby the cheek pieces are connected with the nose band at opposite sides thereof, a clamp plate on the first mentioned rope at the intersection of the portions of said rope constituting the cheek 20 piece, the throat latch and the crown, and a clamp plate by means of which the loop of the cheek piece formed by the last mentioned rope is connected adjustably with the looped extension of the crown, said 25 looped extension being provided with a clamp ring to retain it in adjusted position.
2. A halter composed of two pieces of rope, one piece being folded to produce a cheek piece having a loop at its lower end, a crown having a looped extension, a throat 30 latch having a loop, and a looped shank depending from the throat latch; the other piece being folded to produce a cheek piece having a loop at its upper end, and a nose band, the latter including two coils of rope, 35 clamp members whereby the cheek pieces are connected with the nose band at opposite sides thereof, a clamp plate on the first mentioned rope at the intersection of the 40 portions of said rope constituting the cheek piece, the throat latch and the crown, and a clamp plate by means of which the loop of the cheek piece formed by the last mentioned rope is connected adjustably with the looped extension of the crown, said 45 looped extension being provided with a clamp ring to retain it in adjusted position, the looped shank depending from the throat 50 latch having a guide ring through which a looped portion of the nose band is guided, and said looped portion of the nose band having a tie ring to prevent the withdrawal 55 thereof through the guide ring and for the attachment of a tie rope.
3. A halter composed of two pieces of rope, one piece being folded to produce a cheek piece having a loop at its lower end, a crown having a looped extension, a throat 60 latch having a loop, and a looped shank depending from the throat latch; the other piece being folded to produce a cheek piece having a loop at its upper end, and a nose 65 band, the latter including two coils of rope, clamp members whereby the cheek pieces are connected with the nose band at opposite sides thereof, a clamp plate on the first mentioned rope at the intersection of the portions of said rope constituting the cheek piece, the throat latch and the crown, and a clamp plate by means of which the loop of the cheek piece formed by the last mentioned rope is connected adjustably with the looped extension of the crown, said 70 looped extension being provided with a clamp ring to retain it in adjusted position, the looped shank depending from the throat latch having a guide ring through which a looped portion of the nose band is guided, and said looped portion of the nose band having a tie ring to prevent the withdrawal 75 thereof through the guide ring and for the attachment of a tie rope.
4. A halter composed of two pieces of rope, one piece being folded to produce a cheek piece having a loop at its lower end, a crown having a looped extension, a throat 80 latch having a loop, and a looped shank depending from the throat latch; the other piece being folded to produce a cheek piece having a loop at its upper end, and a nose band, the latter including two coils of rope, 85 clamp members whereby the cheek pieces are connected with the nose band at opposite sides thereof, a clamp plate on the first mentioned rope at the intersection of the portions of said rope constituting the cheek piece, the throat latch, and the crown, and a clamp plate by means of which the loop of the cheek piece formed by the last mentioned rope is connected adjustably with the looped extension of the crown, said 90 looped extension being provided with a clamp ring to retain it in adjusted position, the looped shank depending from the throat latch having a guide ring through which a looped portion of the nose band is guided, and said looped portion of the nose band having a tie ring to prevent the withdrawal 95 thereof through the guide ring and for the attachment of a tie rope.
5. A rope halter including a crown formed of an elongated looped rope portion, a cheek piece formed of a looped rope portion, a clamp plate having a sleeve engaging the loop of the cheek piece, and additional substantially parallel sleeves through which the side portions of the loop constituting the crown are guided, the portion of the loop projecting beyond said 100 sleeves being provided with a clamp ring adjustable thereon to prevent the withdrawal of said portions through the sleeves.

In testimony whereof I affix my signature in presence of two witnesses.

ARTHUR DREW.
